Attorney

UNITED STATES PATENT OFFICE

JAMES E. GREENAN, OF ASHTON, RHODE ISLAND

CANDLE LAMP

Application filed May 25, 1929. Serial No. 365,955.

My invention relates to candle holders or so-called "candle lamps".

An object of my invention is to provide a candle holder so constructed that the candle held therein will consume all of its own drippings so that it burns to the very end and there is consequently no residue but a shred of wick. A further object of my invention is to provide a candle holder wherein the candle there-
10 of when almost consumed is retained upright in a socket portion with the lower end thereof in a well containing molten wax from the candle drippings and so constructed that as the drippings from the candle in and around
15 the socket get hot and liquefied they run down into the chamber or well under the socket and hence under the candle wick so that when the candle is almost consumed the candle holder becomes an oil or molten wax lamp with the
20 wick held upright in the socket standing in a chamber of liquefied wax until the wax is consumed completely.

A further object of my invention is to provide a candle holder which may successively
25 burn a plurality of candles without cleaning or any other operation than the mere insertion of a new candle therein, each successive ignited wick soaking up the liquid wax and feeding it to the flame of each succeeding wick
30 with the wick successively falling down into the well below without interfering with the setting of the new candle, thereby causing the accumulated wicks to form a successively larger wick for the burning of the oil therein
35 as in an oil lamp.

A further object of my invention is to so construct a candle holder that the heat from the burning candle will tend to keep the wax molten in the chamber thereof and wherein
40 heat is conserved through the conductivity of the holder and led to the molten wax chamber thereof.

These and such other objects of my invention as may hereinafter appear will be best
45 understood from a description of the accompanying drawings which illustrate an embodiment thereof.

In the drawings, Fig. 1 is a side elevation of my improved candle holder containing a
50 candle actually mounted on a votive stand.

Fig. 2 is a plan view thereof with the candle removed.

Fig. 3 is a sectional view thereof showing how the candle holder functions as a lamp when the candle itself has changed from solid
55 to liquid form.

Fig. 4 is a disassembled perspective view of the cup and socket members of my invention.

Fig. 5 is a perspective view of an alternative
60 form of a socket member which may be employed.

In the drawings, wherein like characters of reference indicate like parts throughout, 65
10 generally indicates my improved candle holder. My improved candle holder preferably consists of two members, the cup member 12 and the socket member 14. The cup member is preferably constructed of an irregularly downwardly tapering conical shape
70 and is provided with means at the lower end thereof for mounting thereof on a base such as the well 16 formed in the lower end thereof adapted to compactly fit in a suitable hole 18 normally provided therefor in a standard
75 type of votive stand 20. Said cup member is provided with the inwardly projecting lip 22 spaced from the lower end 24 thereof forming the interior or socket seat and the exterior cup member seat 23 and the lower compartment or well 16 below said lip 22. The cup member is also preferably provided with the cylindrical socket holding portion 28 above
80 said seat 22 and preferably provided with the outwardly tapered portion 30 above said cylindrical portion 28. In order to conserve
85 the heat and lead it by the conductivity of the metal of the cup member to the well 16, I preferably provide my improved cup member 12 with the inwardly projecting baffle lip
90 32 above said tapered portion 30. The upper portion of the cup member is provided with the flaring portion 34 above said baffle lip 32 for ornamental purposes flared to catch falling
95 wax and pitched at such an angle that the wax runs down into the well as soon as the flame heats the baffle lip as the candle has burned down in use.

I also provide for use with said cup member or for other forms of holders employed if
100

desired, the generally cylindrical hollow socket member 14. Said hollow socket member 14 is provided with the base 36 preferably comprising the downwardly extending 5 annular flange 36 adapted to seat on the socket seat 22 of the cup member 12. The socket member 14 is preferably provided above said base 36 with the inwardly projecting annular portion 38. The side walls of said socket member are preferably provided with holes to 10 permit the free flow of molten wax from the upper portion of the cup member 12 into the well 16 of the cup member, in my preferred embodiment said holes taking the form of the 15 vertical holes 39 in the annular portion 38 for the free flow of molten wax therethrough. Said socket member 14 is provided with the outwardly tapering portion 40 forming the candle seat above said annular portion and 20 the cylindrical candle holding and wick supporting portion 42 above said seat and an upper portion 44 preferably so outwardly flared that it guides the heat up under the baffle lip 32. I have shown in Fig. 5 an alternative 25 form of socket member having the base 36 and side walls thereof enlarged to hold a larger type of candle and still be adapted to be held in the standard type of cup member 12 shown. In this embodiment the upper 30 candle holding portion 42 thereof is larger than the base 36 thereof and lower side walls thereof and the lower end 48 of the base thereof may be closed if desired as shown forming a well in the lower portion thereof.

35 In operation, the candle 50 has the lower end thereof suitably inserted in the candle holder 14 to rest on the candle seat 40 thereof. The wick 52 of the candle is then lighted as usual and the candle permitted to burn. 40 As the candle is almost consumed as shown in Fig. 3 the heat from the flame 54 thereof heats the entire socket member 14 and also the adjacent portions of the cup member 12 particularly the inwardly projecting baffle 45 lip 32 thereof which conducts the heat to the well 16 thereof and also to the flared portion 34 of said cup member, thus melting and precipitating all wax into the well and the portion thereof adjacent said socket member to 50 tend to liquefy the wax 56 in the well 16. As the entire wax 56 becomes molten as shown in Fig. 3 it is obvious that it will flow freely through the holes 39 back and forth from the well 16. Whatever portions of the wax 55 formed on the cup or socket members during the initial burning of the candle becoming also liquefied. As shown in Fig. 3 it is obvious that the side walls 42 of the socket member 14 will successively support the shreds of wicks 52 so that the upper ends thereof may still burn above the molten wax and so that the lower ends thereof will lie in the molten wax. As previously stated thus 60 each candle burns until the wax thereof is substantially consumed leaving in the well 16

a small amount of molten wax and a plurality of burning shreds of wicks 52 as the candles 50 are burned. It is apparent that each successive shred of wick 52 thereof will tend to form a larger composite wick for the 70 well 16.

It is thus obvious that I have provided a novel type of candle holder easy to construct and which functions to consume substantially all of the wax of the candle thereof to the 75 last drop.

It is understood that my invention is not limited to the specific embodiments shown and that various deviations may be made therefrom without departing from the spirit 80 and scope of the appended claims.

What I claim is:

1. A candle holder comprising in combination, an irregularly tapering conical cup member having an annular inwardly projecting seat and a lower compartment below said seat adapted to form a well for the reception of burnt wicks and molten wax and a substantially cylindrical socket member holding portion above said seat and a substantially cylindrical hollow socket member adapted to hold a lower end of a candle having a base adapted to rest on said seat, a portion of said socket member forming a seat for the lower end of the candle and a candle holding portion above said seat, said portion also serving to support the wick when the candle wax has become molten.

2. A candle holder having means at the lower end for mounting on a base, an annular inwardly projecting lip spaced from the lower end thereof forming a seat and a lower compartment below said lip adapted to form a well for the reception of burnt wicks and molten wax, a cylindrical portion above said seat, an outwardly tapering portion above said cylindrical portion, an inwardly projecting baffle lip above said tapering portion and an upper outwardly flaring portion above said baffle lip.

3. A cylindrical hollow socket member adapted to hold the lower end of a candle having an annular downwardly extending base, an inwardly projecting annular portion above said base having vertical holes for the free flow of molten wax therethrough, an outwardly tapering portion forming a candle seat above said annular portion and a cylindrical candle holding portion above said seat, said portion also serving to support the wick when the candle wax has become molten.

4. A cylindrical hollow socket member for use in holding candles having a base, an inwardly projecting annular portion above said base having axial holes for the free flow of molten wax therethrough, an outwardly tapering portion forming a candle seat above said annular portion and a cylindrical candle holding portion above said seat, said portion

also serving to support the wick when the candle wax has become molten.

5. A candle holder comprising, in combination, a cup member having means on the lower end thereof for mounting on a base, a seat spaced from the lower end thereof, a well below said seat, a socket holding portion above said seat and an inwardly projecting baffle lip therein above said socket holding portion and a detachable hollow socket member of a shape to hold and support the lower end of a candle and the wick thereof therein having a base adapted to permanently seat on the seat in the cup member, a candle seat and holes in the side walls thereof for the free passage of molten wax therethrough.

6. A candle holder, comprising, in combination, a cup member having a seat spaced from the lower end thereof, a well below said seat and a hollow socket member of a shape to hold and support the lower end of a candle having a base adapted to seat in the socket seat of the cup member and a seat on said socket member adapted to support a candle.

23 In testimony whereof I affix my signature.
JAMES E. GREENAN.
